(57) **CLAIM**

The ornamental design for a container handle, as shown and described.

DESCRIPTION

FIG. 1 is perspective view of the handle, the broken line illustrating environmental structure;

FIG. 2 is perspective view of the handle;

FIG. 3 is an end view of the handle of FIG. 2;

FIG. 4 is a top view of the handle of FIG. 2;

FIG. 5 is a side view of the handle of FIG. 2;

FIG. 6 is a bottom view of the handle of FIG. 2;

FIG. 7 is a transverse view along line 7-7 of FIG. 2; and,

FIG. 8 is a transverse view along line 8-8 of FIG. 2.

The handle is shown fragmented to indicate non-specified length.

The broken line forms no part of the claimed design.
